CLEANING HEAD FOR BLACKBOARD RENOVATORS

Filed April 15, 1925

INVENTOR
Albert P. Bennington
By W. W. Williamson Atty.

UNITED STATES PATENT OFFICE.

ALBERT P. BENNINGTON, OF PHILADELPHIA, PENNSYLVANIA.

CLEANING HEAD FOR BLACKBOARD RENOVATORS.

Application filed April 15, 1925. Serial No. 23,216.

My invention relates to new and useful improvements in a cleaning head for blackboard renovators, which embodies a rotary member adapted to carry interchangeable cleaning devices and located within a casing jacket which acts as a conduit for material drawn inward by a suction device, and has for its primary object to provide an improved means for detachably mounting the cleaning devices, such as flexible abrasive discs, in conjunction with a backing member onto the rotating member.

Another object of the invention is to provide a rotating member with a recess to receive a compressible backing member and thereby partially house said backing member, superimposing a flexible abrasive disc over the backing member and clamping said flexible abrasive disc between the backing member and a clamping device detachably mounted on the rotating member.

A further object of the invention is to provide, in combination, a rotating disc having a cavity therein, a compressible backing member partially housed in said cavity, a flexible disc superimposed on said backing member and a clamping ring detachably mounted on the rotatable disc and provided with a flange of sufficient width to overlie the backing member so that when the clamping ring is forced home the backing member will be compressed with the flexible disc between said backing member and the clamping ring so as to be resiliently held in position.

With these ends in view, this invention consists in the details of construction and combination of elements hereinafter set forth and then specifically designated by the claim.

In order that those skilled in the art to which this invention appertains, may understand how to make and use the same, I will describe its construction in detail, referring by numerals to the accompanying drawing forming a part of this application, in which:

Fig. 1, is a longitudinal sectional view of a cleaning head for blackboard renovators illustrating the embodiment of my invention with parts of said cleaning head shown in elevation for convenience of illustration.

Fig. 2, is a section at the line 2—2 of Fig. 1.

In carrying out my invention as here embodied, 2 represents a head for the black-

board renovator as a whole and includes a casing or jacket 3 constructed of generally tubular formation open at both ends and consisting of a body 4 from one end of which projects a reduced shank 5 and from the opposite end projects the enlarged bell 6 to produce a mouth 7 for the entrance of particles drawn into the casing or jacket by means of a suitable suction device connected in any suitable manner with the casing or jacket as by a flexible tube or conduit, slipped over the shank 5. The rear wall 8 of the bell 6 is preferably flared outward or is of outwardly divergent formation and in this wall 8 of the bell is formed a hole 9 for a purpose to be later described and if found desirable said wall may be strengthened in the locality of said hole by the formation of a lug 10. Within the body portion 4 are formed a plurality of longitudinal ribs 11, preferably three in number, spaced about the inner circumference of said body portion so as to form the passageways 12 between the several ribs as plainly shown in Fig. 2. In the body portion, and preferably in the region of one of the ribs is formed a threaded hole 13 in which is positioned the set screw 14 for coaction with the annular exterior groove 15 intermediate the ends of the barrel 16 for positioning said barrel lengthwise and holding the same stationary between the ribs 11, as plainly shown in Fig. 2.

The barrel 16 is open at its inner end 17 where it is internally threaded as indicated at 18 while the outer end is partially closed by an end wall or inturned flange 19 in which is provided a hole 19. In this barrel is located the stub or rigid shaft 20 having a threaded inner end 21, a threaded outer end 22 and a collar 23 adjacent said outer end, which collar is located in the hole 19 but is of sufficient width or thickness that one face projects outside and the other face inside of the end wall 19. On the rigid shaft between the collar 23 and the inner end of said shaft is mounted a ball bearing 24 so as to abut the inner face of said collar 23 in cooperative relation to the shaft and barrel and as said ball bearing is of usual construction including two rings and balls it will not be described in detail. A tubular spacer washer 25 surrounds the shaft 20 with one end in engagement with the ball bearing 24 while another ball bearing 26, exactly like the bearing 24, surrounds the

rigid shaft and engages the opposite end of the tubular spacer washer and these parts are held in place by a nut 27 having threaded engagement with the threaded inner end 21 of the shaft. In order to fill the space between the end wall or flange 18 of the barrel 16 and the outermost bearing 24 a compressible washer 28 is interposed between said end wall 18 and a metallic washer 29 coating with the outer face of the bearing 24.

The reference numeral 30 represents a flexible shaft of any well known make or construction to an end of which is fixed one end 15 of a tubular connector 31 while the opposite end of said connector is externally threaded for threaded connection with the rigid shaft 20 by means of its threads 21 and said tubular connector is provided with an external spiral groove 32 which acts as a 20 conveyor to urge any matter outward with relation to the lower end of the barrel 16 as will be hereinafter more fully explained.

The flexible shaft 30 is surrounded by a flexible sheath 33, generally constructed of latticed or interlaced metal strips and one end of this sheath is fixed to the tubular terminal 34 having threaded connection, as indicated at 35 with the smaller end of the reducing coupling 36 which in turn has threaded connection with the inner end of the barrel 16 by means of its threads 17 and the end of said reducing coupling which connects with the barrel 16 is preferably reduced in diameter to form the shoulder 37 which will engage the inner end of the barrel 16 and thereby determine the position of the coupling relative to the barrel. The coupling has a bore 38 in which the connector 40 31 snugly fits and therefore any matter which may attempt to enter the coupling will be carried back into the sheath 16 of the terminal by means of the spiral conveying groove 32 as will be obvious.

On the outer end of the rigid shaft 20 is fitted the rotating disc 39, clamped solidly against the collar 23 of the shaft by means of a nut 40 screwed onto the threaded end 22 and this rotating disc preferably is provided with a hub 41 which engages the collar 23. Between the disc, and more particularly its hub, and the end wall or flange 18 of the barrel is interposed a compressible washer 42, such as a felt washer, to occupy the space 55 between the end wall 18 and the rotating disc and prevent the accumulation or entrance of dust or other foreign matter about the working parts.

The rotating disc has a central cavity 43 thereby providing an annular flange 44 at right angles to the main portion of the disc and a face of this flange is beveled or inclined as at 45. About the periphery of the rotating disc are located a plurality of spaced radial pins 46.

In the cavity 43 is located a compressible backing member 47 of sufficient thickness to project considerably beyond the annular flange 44 and said backing member has an aperture 48 for registration with the outer end 70 of the rigid shaft and the nut thereon. A flexible abrasive disc 49 is placed over the exposed portion of the backing member 47 the same being clamped onto the backing member by means of the clamping ring 50 75 which includes the annulus 51 to surround the perimeter of the rotating disc and an inwardly projecting flange 52 which is of sufficient width to project beyond the flange 44 of the rotating disc so as to overlap the 80 edge of the backing member and that portion of the edge of the abrasive disc in the same region. In order to detachably connect the clamping ring to the rotating disc the annulus thereof is provided with a plurality of inclined slots 53 corresponding in number to the pins 46 and positioned for cooperation therewith so that after the backing member and an abrasive disc are positioned and the clamping ring placed thereover so that the entrances to the slots 53 register with the pins 46 a slight turn of the clamping ring will draw its flange downward or inward so as to compress the outer edge of the backing member 46 and at the 90 same time force the edge of the abrasive disc onto the compressed part of the backing member to thus clamp the abrasive disc and backing member on the rotating disc. In order to insure holding the clamping ring 100 in position on the rotating disc an edge of the annulus wall in the region of each inclined slot is serrated as at 54.

The flexible backing member 47 must be sufficiently resilient as to be readily compressible and tend to force the abrasive disc outward when the latter is clamped in place so as to keep the serrations 54 in engagement with the pins 46 for holding the clamping ring on the rotating disc and also 110 to cause the abrasive disc to enter depressions in the blackboard surface being cleaned.

To place the clamping ring upon the rotating disc or remove it therefrom it is 115 necessary to hold said rotating disc stationary which is accomplished by passing the holding rod 55 through the hole 9 in the rear wall of the closing bell and inserting the inner end of said holding rod in the hole 56 formed in the rotating disc and more particularly in the hub of said disc, said hole being so arranged as to align with the hole 9 and while I have shown but one hole 56 it will be understood that two or more of these might be provided without departing from the invention.

From the foregoing description it will be obvious to persons familiar with this art that when the holding rod 55 is in the posi- 120

tion illustrated the rotating disc 39 will be held stationary relative to the casing or jacket 3 and that by turning the clamping ring 50 in the proper direction the latter 5 may be placed upon or removed from the rotating disc which will permit the placement removal or renewal of the abrasive disc. When the device is in use the holding pin 55 is entirely removed and the rotating disc is revolved by a suitable prime mover transmitting its motion through the flexible shaft 30, its connector 31 and the rigid shaft 20. As the working face of the abrasive disc is at right angles to the axis 10 of rotation the cleaning head is held against a blackboard with the axial center of the head at right angles to the blackboard surface. During the cleaning operations the dirt, dust, particles of blackboard and other 15 foreign substances will be dislodged and drawn into the bell of the jacket by means of the suction device with which said jacket is connected, after which it will be carried off through the passageways 12 between the ribs 11 in the body of the jacket 20 and then through the shaft of said jacket to a suitable conduit through which it passes to a suitable receptacle.

It is to be understood that when the conduit is connected with the jacket the flexible shaft and its sheath are enclosed by the conduit. By removing the set screw 14 the 25 casing or jacket 3 may be forced back over the flexible shaft and its sheath a sufficient distance to obtain access to the coupling 30 36 so that it may be screwed out of the barrel 16. After this has been done the coupling 36 may be moved away from the barrel by slightly distending the flexible shaft and 35 simultaneously compressing the sheath 33 which will make connector 31 accessible so that it may be removed from the rigid shaft 40

20. The parts being thus disconnected the barrel 16 with the rotating disc and their component parts may be separated from the 45 casing or jacket and the latter also withdrawn from the flexible shaft and its component parts.

If it is desired to disassemble the bearings then the nut 40 is removed so that the 50 rotating disc can be withdrawn from the outer end of the rigid shaft and then said rigid shaft with the bearings intact can be withdrawn from the inner end of the barrel. When this has been done the nut 27 55 may be removed and the bearings slipped off of the rigid shaft along with the spacer washer 25.

Of course I do not wish to be limited to the exact details of construction as herein 60 shown as these may be varied within the limits of the appended claim without departing from the spirit of my invention.

Having thus fully described my invention, what I claim as new and useful is:— 65

A cleaning head for blackboard renovators comprising a rotatable disk, a compressible backing member carried by said disk, a sheet of abrasive material covering the backing member and extending over a portion of the disk, pins projecting from the periphery of the disk and a ring for clamping the backing member and the abrasive material to the disk, said ring having inclined slots therein opening out through an 75 edge of the ring, the bottom wall of each slot being corrugated so that when the pins enter the slots, they will engage the corrugated portions and thus hold the ring in adjusted position on the disk. 80

In testimony whereof, I have hereunto affixed my signature.

ALBERT P. BENNINGTON.
